PROCESS OF ROUTING ARTICLES THROUGH
A FURNACE

Roy C. Ingersoll, Oak Park, Ill., assignor to Borg-Warner Corporation, a corporation of Illinois

Application December 30, 1936, Serial No. 118,312

4 Claims. (CL 25—157)

This invention has to do with the processing of material by subjection to heat, and relates particularly to improvements in the mode of moving the material thereby effecting a diminution in heat loss. For example, the present invention may be applied in the art of preparing enamelled surfaces upon articles of manufacture or the like. Almost universally enamelware is baked in a box furnace into which the articles to be treated are introduced through an opening and later removed through the same opening. This method in addition to being slow and making but an inefficient use of the furnace has the further undesirable feature of causing sudden temperature changes in the enamelware. Articles which have been coated with "green" enamel are preferably gradually brought up to a temperature at which such enamel will become hardened by baking and then gradually cooled to room temperature. This process in a few instances has been successfully performed in large continuous type of ovens or furnaces through which a line of freshly coated articles are successively transported within a space having a temperature gradient which first increases in the direction of the line movement and then decreases in the direction of line movement toward an oven exit. Usually in such ovens portions of the lines of ingress and egress are in close proximity so that incoming articles will absorb heat from and gradually cool those being carried toward the oven exit. Obviously the large amount of space required for an oven of this type and the original cost of such an installation are objectionable factors.

Another object of the present invention is the provision of an expedient method of recouping heat from furnace treated articles for energizing a pre-heater chamber wherein succeeding articles are heated prior to disposal in such furnace.

Still another object of the present invention is the provision of a novel method of heat treating articles by introducing successive groups thereof into an oven and withdrawing the same from the oven into a position below succeeding untreated articles for preheating them prior to their advancement into the oven.

Other objects of the invention will become apparent upon reading the following description with reference to the accompanying drawings, wherein:

Fig. 1 is a fragmentary side elevation of a unitary structure of firing chamber and preheating chambers, a side wall of the furnace

and preheating chambers being removed to expose the interior of the unit;

Fig. 2 is a transverse sectional view taken on the line 2—2 of Fig. 1; and

Fig. 3 consists of a series of diagrammatic representations chronologically illustrating the several stages included in a preferred operating cycle of the apparatus shown in Figs. 1 and 2.

Like parts shown in the various figures of the drawings and referred to hereinafter are designated by the same reference characters. The invention will be described as it may be applied to a specific installation of a furnace comprising a firing chamber having heat recuperating chambers upon opposite sides thereof. The particular illustrative installation is designed for handling washing machine tubs which are coated with a suitable substance adapted to be baked for forming a hard enamel surface when subjected to adequate heat. It is to be understood, however, that the apparatus and process may be modified to extend to heat treatment of other articles or materials without departing from the spirit of the invention.

Referring now to Fig. 1, there will be seen a furnace 10 resting upon a foundation 11. End walls 12 and 13 of the furnace have therein openings 14 and 15 which may be closed by vertically movable doors 16 and 17. A conventional style of furnace burner is indicated at 18.

Identical heat recuperator or preheating chambers 19 and 20 are arranged oppositely with respect to the firing chamber 10. The openings 14 and 15 in firing chamber 10 communicate respectively with the chambers 19 and 20 when the firing chamber doors 16 and 17 are raised by means of cables 21 and 22 which are adapted to be wound upon drums 23 and 24. Openings 25 and 26, closable by doors 27 and 28, are provided in the preheating chambers 19 and 20. Said doors 27 and 28 are adapted to be elevated by means of cables 29 and 30 which are adapted to be wrapped about drums 31 and 32.

A conveyor comprised of endless chains 33 is engaged by driving sprockets 34 and 35. The upper spans 36 of the chains 33 are maintained in a common horizontal plane by means of channels 37, which longitudinally traverse the entire unit. Channels 37 are in alignment with and extend through the doors 14 and 15 of the furnace 10. A series of short upright brackets 38, Figs. 1 and 2, are secured at intervals upon the floors of the chambers for supporting the channels 37. Similar brackets 39 may be anchored in the foundation 11 for supporting channels 40, which serve

as guides for the lower spans of the chains 33.

The material or articles to be handled by the equipment shown in Figs. 1 and 2 is carried upon sets of racks or burning bars 41. Said sets are designated respectively A, B, C and D. Each burning bar 41 has upright pointed pins 41a for supporting an article 42 in a manner making contact with a minimum of the area thereof. The size of the present unit of firing chamber and preheater chambers is such as to accommodate sets A, B, C and D each of which consists of five burning bars. Obviously the size and number of burning bars in a set may be changed and still remain within the scope of the invention.

Upon referring to Fig. 2, it will be seen that each burning bar 41 is adapted to support two articles to be treated by the furnace, and that such burning bars extend transversely of the chains 33. Also in Fig. 2, it will be noticed that the ends of the burning bars 41 project beyond the chains 33 so that such ends may be engaged on their underside by the horizontal wings of angle pieces 43 carried by a cradle 44. Cradle 44 is supported upon cables 45, which are adapted to be wound upon drums 46 carried by a shaft 47. Power driving means including gearing 48 is adapted to rotate the shaft 47 and the drums 46 for raising and lowering the cradle 44 by means of the cables 45. The cradle 44 is illustrated in Fig. 2 as supporting group B of the burning bars in the upper part of the preheating chamber 19. Group D of burning bars 41 is shown in Fig. 1 as supported in the upper part of preheating chamber 20 by a similar cradle device of which only the angle member 43 is shown.

Prior to their introduction into the preheating chambers of the device, the tubs 42 are loaded onto a set of burning bars 41 which are resting upon a charging fork 49 or 50, Fig. 1. Subsequent to loading a group of burning bars carrying tubs 42 upon a fork 49 or 50, the chamber door 27 or 28 is opened and the fork projected into its chamber 19 or 20. The fork is then lowered whereby to deposit the group of burning bars upon the conveyor chains 33. The fork is then withdrawn and the chamber door closed. While the load is being deposited within a chamber the cradle 44 therein is in its lowermost position so that the load is actually deposited within the confines of a cradle. As soon as the loading fork has been withdrawn from the chamber the cradle 44 is elevated to lift the group of burning bars and articles 42 thereon after the fashion illustrated in Fig. 2. Thereafter, a load of treated articles is withdrawn from the firing chamber 10 and deposited within the preheating chamber beneath the articles which have just been elevated. The door 16 or 17 of the firing chamber 10 is closed behind the articles moved therefrom into the chamber 19 or 20, said articles being permitted to remain in the chamber to give up part of their heat for preheating the elevated articles. Eventually, the fired articles are removed from the preheating chamber by means of a fork 49 or 50. The removed articles are then taken from the burning bars and replaced by fresh articles which are later inserted into the preheating chamber and elevated.

A coordinated order of manipulating the various groups of burning bars as an incident to carrying out the improved process will best be understood by reference to Fig. 3 where the sixteen successive stages of a preferred cycle are shown. The groups of burning bars are there designated A, B, C and D as in Figs. 1 and 2. In

the inception it should be conceived that groups A and B are rotatively shifted between positions at the left-hand load and unload end of the unit, in the preheating chamber 19 and in the firing chamber 10; whereas groups C and D are similarly rotated between positions at the right load and unload end of the unit in the preheating chamber 20 and in the firing chamber 10. Burning bar groups A and C are shifted into the firing chamber 10 alternately with groups 10 C and D, but said groups are always returned to their respective preheating chambers and carried out to their respective positions for load and unload.

The conveyor chains 33 are reversible in their movement, the movement being intermittent. For example, the conveyor will function to carry a group of burning bars from a preheating chamber into the firing chamber, and then stop and remain quiescent until time for the group to be returned to the preheating chamber from which it had been taken, at which time the conveyor will be given a reverse movement.

While the conveyor is moving for shifting groups of burning bars, both firing chamber doors 16 and 17 are open, so that incident to carrying one group of burning bars into the firing chamber from one of the preheating chambers, a group of burning bars carrying a load of treated articles will be removed from the firing chamber into the opposite preheating chamber. Upon the completion of the movement of the conveyor the firing chamber doors 16 and 17 will be closed. At no time is a preheater door 27 or 28 open while the opposite firing chamber door 16 or 17 is open, this precaution being taken so as to conserve heat which may otherwise be lost through radiation. Inasmuch as any conventionally controlled driving means may be employed for reversibly driving the chains 33 of the conveyor, no means is illustrated in this application.

Referring now to the first stage shown in Fig. 3, the arrow indicates that group A of burning bars has just been removed from preheating chamber 19 and disposed at the left end of the unit for having unloaded therefrom articles which have been treated in the firing chamber 10, and for reloading with fresh articles. Group B of burning bars has remained in the elevated position in preheating chamber 19 while the load A was removed through chamber opening 25 by means of the loading fork 49. Group C of loaded burning bars is in the firing chamber, and Group D of such bars is in the elevated position in preheating chamber 20.

In the next or second stage of the cycle, group A remains in position for unloading and reloading. Group B has been lowered, as indicated by the arrow, from the position shown in stage 1 to the lower position in preheating chamber 19. Groups C and D remain as in the first stage.

In the third stage, groups B and C which have been resting upon the conveyor chains 33 are moved through firing chamber door openings 14 and 15 by a movement of the conveyor and placed in the positions indicated by the arrows. As soon as groups B and C are thus placed, the firing chamber doors 16 and 17 are immediately closed. By this time group A has been loaded with fresh articles prepared for heat treatment whereupon such articles are issued into the preheating chamber 19 and elevated as indicated by the arrow in stage 4. Meanwhile, the heat from group C has been heating the chamber 20. 75

As the cycle proceeds, however, group C is removed from the chamber 20 as shown by the arrow of stage 5.

In the next stage, stage 6, group D is lowered as indicated by the arrow, this group having been preheated during the five preceding stages. Lowered group D is placed upon the conveyor chains 33 for movement thereby into the firing chamber 10 as shown in stage 7. It will be noted that when the conveyor reversed its movement for moving group D into the firing chamber, both firing chamber doors 16 and 17 were raised so that group B was concurrently carried out of the firing chamber. The heated load of articles in group B then serve to give out heat in the preheating chamber 19 to further preheat the articles in group A.

During stages 6 and 7 group C is unloaded and loaded with fresh articles, and during stage 8, group C is issued into the preheating chamber 20 and elevated. Next stage 9, group B is taken from preheating chamber 19 and group A is lowered upon the conveyor as shown in stage 10. Groups A and D are then resting upon the conveyor in readiness to be shifted to the right as shown in stage 11, whereby group A is moved into the firing chamber, and group D is moved into the preheating chamber 20 for imparting heat thereto. During stages 10 and 11, group B was unloaded and loaded with fresh articles, and during stage 12 said group is issued into the preheating chamber 19 and elevated. By the time of arrival for stage 13, group D has heated the preheating chamber 20 and is removed therefrom as shown by the arrow. In stage 14 group C is shown to have been lowered upon the conveyor, whereby such group C which has been preheated may be moved into the firing chamber concurrently with the removal of group A from the firing chamber incident to the movement of the conveyor as indicated by the arrows in stage 15. Group D, which has then been unloaded and loaded with fresh articles for heat treatment, is then issued into preheating chamber 20 as shown in stage 16. Stage 16 completes the cycle. Repetition of the cycle is commenced by removing group A from the preheating chamber 19 to the position shown in stage 1. The process may then proceed through the various stages in the manner above described.

Although this specification shows and describes a chain conveyor for moving the material into and out of the furnace 10, it is to be understood that any other suitable means such as hearth furnace rollers, carrying cradles, a unit comprised of burning bar and cradle may be used. When, for example, hearth furnace rollers (or any kind of support means having slight resistance to movement of objects thereover) are used instead of a chain conveyor for supporting the groups of burning bars within the preheaters and firing chamber, the loading forks 49 and 50 may be employed for inserting and withdrawing the groups into and out of the firing chamber. It will be understood that the hearth rollers will be rotatable about axes disposed transversely of the path traversed by the articles so that the advanced end of a fork 49 or 50 may simply be pressed against an end of a group of burning bars for pushing them from a chamber 19 or 20 into the firing chamber. Both firing chamber doors 16 and 17 will be raised at such time so that the group being pushed into the firing chamber will in turn push against a group just previously treated in the firing chamber whereby the latter

group is ejected into the opposite preheater chamber. Thereafter, the fork is withdrawn and the firing chamber doors 16 and 17 closed as well as the door 27 or 28 through which the charging fork had been projected. The manner in which the hearth rollers and charging fork may be used in the process in place of the chain conveyor is further exemplified by reference to positions 2, 3 and 4 of Fig. 3. In position 2 the fork 49 is loaded with untreated articles; group B has been lowered in readiness for movement into the firing chamber 10; and group C is in condition for movement from the firing chamber. Preheater door 27 and firing chamber doors 16 and 17 are now opened while the fork 49 is advanced to the right for depositing group A in preheater 19 and for moving groups B and C respectively into the firing chamber and into the preheater 20 as illustrated in position 3. The charging fork is then withdrawn, doors 16, 17 and 27 closed, and group A elevated as shown in position 4. A previous explanation has been given with respect to the manner in which the charging fork 50 removes group C from preheater chamber 20 as shown in position 5. After group C has been reloaded the charging fork 50 is used for introducing such group into preheater 20 while at the same time shifting groups B and D in the manner indicated by the arrows in position 7, and as hereinabove described in connection with position 3. It will be seen, therefore, that the process may be carried on by means of hearth rollers and the charging forks in substantially the same manner as when the reversible chain conveyor is used for shifting the various groups of burning bars.

Articles which have been placed in a preheater gather heat from articles thereunder which have just been removed from the firing chamber and also absorb such heat as is released into the preheater through the opening 14 or 15 during the periods the door for such opening is raised. The articles supported in the upper part of a preheater chamber benefit from articles removed from the firing chamber and placed thereunder, the benefit being derived from the heat absorbed from the lower articles. Meanwhile the temperature of the lower articles is reduced because of the heat given up to the elevated articles, so that it will be seen that the preheater enables the in-going and out-coming articles to mutually benefit from each other. The partially cooled articles emerging from the preheaters do not encounter a too pronounced change in temperature upon being subjected to the atmosphere as may be the case if they were taken directly from the firing chamber without having imparted some of their heat to the in-going articles.

A more efficient transfer of heat from the lower to the upper articles is had because of their relative positions of elevation. The temperature difference in the articles and the air in immediate contact therewith is greater because the cooler articles are in the hottest part of a preheater while the hottest articles are in the coolest part; the heated air immediately rises from the hot lower articles to the cooler upper ones, thus greatly increasing the amount of heat exchange between the articles within a given period.

When consideration is taken of the small size together with the heat conservation faculties of my improved apparatus for carrying out the novel process hereinabove described, special note will be taken of the rapidity with which articles may be treated therein. Although the specific apparatus and process which have been described

are extremely useful it will be understood that the invention is not limited with respect thereto excepting as regards the novel principles underlying the same as set out in the appended claims.

5 I claim:

1. The process of routing articles through a furnace comprising a firing chamber and pre-heating chambers positioned on opposite sides of the firing chamber, said process comprising the 10 steps of charging said firing and preheating chambers with loads of such articles, discharging a heated load of articles from the firing chamber into a preheating chamber on one side of the firing chamber while simultaneously charging the 15 firing chamber with the load from a preheating chamber on the opposite side of said firing chamber, discharging said heated load of articles from said first-mentioned preheating chamber, and discharging said firing chamber of the load from said 20 second mentioned preheating chamber while simultaneously charging said firing chamber with the load first charged into said first-mentioned preheating chamber.
2. The process of routing articles through a 25 furnace comprising a firing chamber and pre-heating chambers positioned on opposite sides of the firing chamber, said process comprising the steps of charging said firing and preheating chambers with loads of such articles, and alter-

nately charging the firing chamber with loads from said preheating chambers, the loads being returned from the firing chamber to the preheating chambers from which they were taken while simultaneously charging the firing chamber with 5 loads from the opposite preheating chamber.

3. The process of routing articles through a furnace comprising a firing chamber and pre-heating chambers positioned on opposite sides of the firing chamber, said process comprising the 10 steps of charging said firing and preheating chambers with loads of such articles, alternately charging the firing chamber with loads from said preheating chambers, the loads being returned from the firing chamber to the preheating chambers from which they were taken while simultaneously charging the firing chamber with loads from the opposite preheating chamber, and discharging a fired load from a preheating chamber while a load from the opposite preheating chamber 15 is being fired.

4. The process of routing articles through a furnace as described in claim 3, and charging the preheating chamber from which a fired load has been discharged with a fresh load to be preheated, 20 said charging being done while a load from the opposite preheating chamber is being fired in the firing chamber.

ROY C. INGERSOLL.
